WATER LINE HEATER FOR VEHICLES
OR THE LIKE

John H. Klanckle, Minneapolis, Minn., assignor to Puratronics Industries, Inc., Minneapolis, Minn., a corporation of Minnesota

Filed Mar. 14, 1969, Ser. No. 16,241

Term of patent 3½ years

Int. Cl. D23—03

U.S. Cl. D23—86

FIG. 1

FIG. 2

FIG. 3

FIG. 4

FIG. 5

FIGURE 1 is a perspective view of a water line heater embodying my design;

FIGURE 2 is a side elevational view thereof;

FIGURE 3 is a top plan view thereof;

FIGURE 4 is a bottom plan view thereof; and

FIGURE 5 is an end elevational view thereof.

A side elevational view viewed from the side opposite that shown in FIGURE 2 is substantially a mirror image thereof.

An end elevational view viewed from the end opposite that shown in FIGURE 2 is substantially a mirror image thereof.

I claim:

The ornamental design for a water line heater for vehicles or the like, as shown and described.
